UNITED STATES PATENT OFFICE

2,473,425

SCREW CAP OPENER

William F. Grant, Miami, Fla.

Application February 9, 1946, Serial No. 646,669

1 Claim. (Cl. 81—3.43)

1

The present invention relates to improvements in closure removing means for containers and the like and more particularly to means for removing screw caps from jars, bottles and other containers.

One of the objects of the present invention is to provide a simple, efficient and inexpensive device of the character described capable of quickly and positively engaging the screw cap and removing or unscrewing the same.

Another object thereof is to provide a cap removing implement having a flexible means adapted to be looped effectively around the cap to be unscrewed.

A further object of this invention is to provide a cap loosening or unscrewing implement with a linked type means of engaging the cap to be removed, which means has one end secured at one point of connection with the implement, and has a free end adapted to be extended through the implement in a loop around said cap in a manner to be firmly anchored frictionally thereto simply by proper manipulation of the implement in the hands of the operator.

A still further object thereof is to provide a screw cap device consisting of a flat handle having a slotted bearing formed at one end thereof into which is passed a linked chain or other flexible member which has one end fixedly secured to said handle as a means of forming a loop of the chain or flexible member around the cap to be removed, so that by manipulation of the chain or flexible member it is propped securely and frictionally in said bearing so as to resist disengagement of the loop from the cap.

Another object thereof is to provide a handle with a flexible element secured at one end thereof, with means allowing the elements to be pulled through the handle after being looped around the cap to be removed from the container, and with means for preventing the free end of the element from accidentally becoming disengaged from the handle.

In the drawings, wherein similar reference characters designate similar parts throughout the respective views, and in which my invention is shown to consist in the combination, arrangement and details of construction.

Figure 1 is a top plan view of my invention.

Figure 2 is a view thereof taken at right angles to Figure 1.

Figure 3 is a fragmental detail view, partly in section showing links of the chain engaged with the handle at two points, and

2

Figure 4 is a fragmentary view of a modification form of flexible element.

In the drawings, which are merely illustrative of my invention the parts thereof are shown to consist of a flat handle member 10 which is preferably formed with an enlargement as at 11, at one end, and is preferably formed, at its opposite end, with a bottle cap removing recess 12 of a well known type.

10 I employ a flexible member, such as a linked chain 14 or flexible element 24 as the means intended to engage the cylindrical surface of the screw jar cap or screw cap of the container which it is desired to unscrew or remove. It is a well known fact that such container caps are quite often stuck upon the usual gasket around the neck of the jar or container so as to resist manual detachment by employing the hands of the operator. In such instances it is necessary to employ extraneous means and my invention is designed to supply same.

For the purpose of furnishing a means of securing removably one end of the linked chain 14 to the handle 10, the handle is formed in its enlargement 11 with a pair of openings 16 struck from the material of the handle, leaving a narrow portion or bridge 17 between them. A portion of one end link 18 of the chain is passed into the opening 16, one side wall on each side of the narrow portion or bridge 17, and a cotter pin or like fastener 19 is inserted through the adjacent link hole and also passed over the bridge 17; this securely yet releasably holds one end of the chain fast upon the handle.

35 The chain is adapted to be extendably secured, ratchet-like into the handle 10 by the following means. I provide in the enlargement 11 of the handle a bayonet-shaped slot which extends transversely of the enlargement so that its narrow portion is disposed in longitudinal alignment with openings 16 as shown in Figure 2 while its wider portion 13 projects laterally of openings 16. At the free or outer end of the linked chain 15 a loop ring 21 is attached, being made of a diameter or size to pass freely into and through the wide portion of slot 13 when the ring is held transversely of the handle, but being incapable of accidentally working through this slot otherwise, when the diameter of the ring is disposed across the length of the slot 13, which is less than the diameter of the ring.

The narrow portion of slot 13 is designated 23. With the inner end of the chain made fast in opening 16, the main body portion or stretch of 55 the chain is adapted to be looped around the jar

or other screw cap to be removed or unscrewed, after which a link 22 thereof which is adjacent to slot 13 is designed to be passed into slot 13. Each link 22 is formed of adjacent side walls, each wall having a narrowed center portion and enlarged ends. The narrow portion of link 22 is then shoved laterally into narrow portion 23 of said slot, by raising the handle about the enlarged end as a pivot after which the chain is drawn tightly around the cap and the enlarged end of link 22 is caused to engage the upper side of slot portion 23 against which it is firmly anchored as shown in Figure 3, so it will not slip and release the hold of the looped portion of the chain around the cap. The operator now holds the container tightly in one hand, by means of the other hand he moves the handle 10 manipulatively in a counter-clockwise direction with sufficient force to loosen the hold of the cap so it unscrews readily. This having been done, the operator takes hold of the ring end of the chain and manipulates same in a manner to disengage link 22 from engagement fixedly in the narrow part 23 of the slot 13.

As a modification of my invention I have shown in Figure 4, a flexible member 24 as rubber, or other suitable material, which may be used in place of the linked chain 14. The member 24 is fastened to the handle 10 by any suitable means and is adapted to pass through the opening 13 in such a manner that the ribs 25 will not pass through the opening 23.

I do not intend to confine myself to the exact details of construction disclosed in the drawings, but claim all variations falling within the purview of the appended claim.

What I desire to claim and secure by Letters Patent is:

A screw cap opener comprising an elongated handle formed with an opening adjacent one end thereof, said opening including a relatively large portion and a relatively narrow portion extend-

ing laterally from one end of said large portion, a flexible cap encircling member, means securing one end of said member to said handle outwardly of said narrow portion and in longitudinal alignment with the latter, said flexible member being formed of spaced elements pivotally joined together by intermediate members, each of said elements having enlarged end portions and a narrow mid-portion, the width of the enlarged end portions being greater than the width of said narrow portion of the opening measured in the direction extending longitudinally of the flexible member and the width of said narrow mid-portions being less than said narrow portion of the opening measured in the same direction, whereby lateral shifting of the flexible member from said large portion of the opening will permit the narrow mid-portions of the elements to slide into said narrow portion of the opening with the said enlarged end portions disposed on opposite faces of said handle and said end portions will be held against passage through said narrow portion of the opening, thus locking the flexible member in its initially tightened condition about the cap.
